(57) CLAIM

The ornamental design for a case for electronic device, as shown and described.

DESCRIPTION

FIG. 1 is a front perspective view of a case, comprised of a transparent cover and three flexible inserts, for an electronic device showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is top plan view thereof; and,

FIG. 8 is a bottom plan thereof.

The broken lines depict a transparent cover showing the locations of the three flexible inserts and forms no part of the claimed design.

1 Claim, 8 Drawing Sheets(56)
